FILLING APPARATUS

Robert J. Stewart, Baltimore, Md., assignor to
 Crown Cork & Seal Company, Inc., Baltimore,
 Md., a corporation of New York

Application May 16, 1936, Serial No. 80,196

12 Claims. (Cl. 226—124)

The present invention relates to apparatus for filling containers such as milk bottles and has particular reference to an improved filling valve arrangement for such apparatus. A principal object of the invention is to provide a valve arrangement of simplified and economical construction, efficient in use, and with few parts readily disassembled for cleaning and readily cleaned.

According to the invention I provide a rubber body which serves as a valve element and also as a sealing element for cooperation with the lip of a container as the latter is being filled. In its office of valve element, the rubber body operates with a portion of a vent or foam tube and improved means are provided for the support of the said tube.

A practical embodiment of the invention is shown by way of example in the accompanying drawing in which:

Figure 1 is a vertical section through the new valve arrangement as applied to a tank, the section being also taken through a bottle which is in filling position and through a table which supports the bottle.

Figure 2 is a vertical section of the valve arrangement on an enlarged scale.

Figure 3 is a section on line 3—3 of Figure 2, and

Figure 4 is a section on line 4—4 of Figure 2.

Referring to the drawing, reference numeral 10 designates a tank which in use may be sealed at the top by a cover 10'. A down-spout 11 comprises a flange 11' which is secured, as by welding, to the bottom of the tank, and a boss portion 12 which has a reduced cylindrical lower extremity 13 surmounted by a downwardly facing shoulder 14. The down-spout has a vertical passage 15 which registers with an opening 16 in the tank bottom. Interiorly the passage 15 is enlarged just above the plane of shoulder 14 to provide an upwardly faced shoulder 17.

Projecting upwardly from the upper portion of passage 15 is a supporting member 18 for a vent or foam tube 19. Member 18 comprises a tubular portion 20 and vertically extending radial ribs 21 which rest on the shoulder 17 and center the tubular portion 20 relative to the passage 15.

The foam tube 19 is slidably received in the tubular portion 20 and is provided with a circumferential groove 22 engaged by the legs of a spring clip 23. The clip rests on top of member 18 and supports the tube 19. With the vent tube thus supported, its lower end projects below the down-spout and is enlarged to form a plug por-

tion 24 serving as a valve seat and for which purpose it has a conical upper surface 25.

A hollow open-ended body 26 of flexible rubber, of substantially the grade commonly used in the sealing ring of the ordinary filling apparatus, has 5 a relatively thick-walled neck portion 27 and a relatively thin-walled bulbiform portion 28. The neck portion is engaged over the reduced portion 13 of the boss and frictionally engages the latter due to its slight distention thereby. The 10 free end of the neck portion abuts the shoulder 14. The portion 28 terminates in an inwardly directed edge 29 which normally contacts the surface 25 to form a seal therewith so that flow through passage 15 is prevented. 15

Portion 28 is constituted by wall portions circumferentially bulged or convexed externally and has an internal annular recess or concavity 30 so that a bottom flange 31 is provided which is externally downwardly tapered at a slight angle 20 to the horizontal. The flange 31 is somewhat thicker at the edge 29 than at its intermediate portion. The top wall of recess 30 is provided with a number of grooves 32 disposed in radial planes. 25

The normal position of the parts is shown in Figure 2 and while member 26 in this view is under some longitudinal compression in order to maintain an adequate contact between edge 29 and surface 25, the form of member 26, when the 30 member is unconfined, is still substantially the same as that shown.

In the operation of the device, a bottle 33 disposed on table 34 is elevated so that the lip 35 of the bottle engages flange 31 somewhat outwardly of plug 24 to form a seal therewith. Flange 31 is then moved upwardly away from surface 25 and may reach the position shown in Figure 1 wherein the top of the flange contacts the top wall of recess 30. Any vacuum effect between the flange and the said top wall is prevented by the vent grooves 32. 40

With flange 31 thus elevated flow takes place from the tank to the bottle through passage 15 and between edge 29 and surface 25. Since the 45 lower edge of the flange is in circumferential contact with the bottle lip a full circumferential seal is obtained so that no leakage can occur at this point, air displaced in the bottle, and foam, rising in the tube 19. When the bottle is completely filled the table 34 is lowered and flange 31 automatically flexes downwardly to bring edge 29 again into sealing contact with surface 25, the bottle lip then releasing the flange. 50

Plug 24 is of such size that in a gravity sys- 55

tem it displaces about the amount of liquid which can return from tube 18 to the bottle as the latter is lowered. In the use of a balanced pressure system slight vacuum is developed in tank 10, just sufficient to prevent the dropping of the foam in tube 19.

5 The thick walls of the neck portion 27 of the rubber body 26 securely grip the boss portion 13 and have a large seating area against shoulder 14 so that the body is effectively positioned. The 10 relatively thin walls of portion 28 readily conform to the container lip to form a complete seal, the contacting surfaces extending inwardly of the lip as shown in Figure 1 due to the increased thickness of the flange at edge 29.

15 In assembly the rubber body is grasped and pushed over boss portion 13 to the position shown. Member 18 being in position in passage 15, the vent tube 19 is inserted upwardly to position and clip 23 engaged therewith. The device is then 20 ready for operation. Disassembly is, of course, accomplished by the reverse process. On the other hand, the rubber body may be pulled downwardly and over plug 24 and thus removed 25 without removing the vent tube. Cleaning or replacement is thus readily accomplished and when body 26 has been removed portion 28 may be turned inside out for cleaning.

Since in the operation of the apparatus there 30 are no moving metal parts and no seating contact of metal parts, it is evident that there is a minimum of wear. The only part which may wear out in use is the rubber valve and sealing member and this is easily and cheaply replaced. 35 Since the down-spout is not subjected to appreciable wear and hence will never need replacing, it may be welded in position, as described, or even be made integral with the tank bottom thus rendering the apparatus more sanitary due to the 40 elimination of the appreciable joint which is present when the down-spout is detachably secured to the tank bottom.

It will be understood that the invention is susceptible of varied embodiment as to form and details of construction and accordingly I do not 45 limit myself except as in the following claims.

I claim:

1. A filling valve comprising a plug, and a flexible resilient body having a passage therethrough, said body having at one end a freely inwardly extending annular flange whose inner edge, which defines a portion of said passage, 50 normally contacts said plug to form a seal therewith, said flange flexing when engaged by the lip of a container during a filling operation to free said edge from the plug to permit flow between said edge and plug, the container lip forming a seal with said flange.

2. A filling valve comprising a plug, and a flexible resilient hollow open-ended body having a neck portion at one end and terminating at the other end in an edge normally in sealing contact with said plug, said body having an internal annular recess inwardly of said edge so that the body portion adjacent said edge is in the 60 form of a freely flexing flange, said flange flexing when engaged by the lip of a container during a filling operation to free said edge from the plug to permit flow between said edge and plug, the container lip forming a seal with said flange.

3. A filling valve comprising a plug, and a flexible resilient hollow open-ended body having a neck portion at one end and terminating at the other end in an edge normally in sealing contact with said plug, said body having an internal 70

annular recess inwardly of said edge so that the body portion adjacent said edge is in the form of a freely flexing flange, said flange being thicker at its edge than at its intermediate portion, said flange flexing when engaged by the lip of a container during a filling operation to free said edge from the plug to permit flow between said edge and plug, the container lip forming a seal with said flange. 5

4. A filling valve comprising a plug, and a flexible resilient hollow open-ended body having a neck portion at one end and terminating at the other end in an edge normally in sealing contact with said plug, said body having an internal annular recess inwardly of said edge so 15 that the body portion adjacent said edge is in the form of a freely flexing flange, said flange flexing when engaged by the lip of a container during a filling operation to free said edge from the plug to permit flow between said edge and plug, the container lip forming a seal with said flange, the wall of said recess opposite said flange being configured to provide a vent so that a vacuum effect is avoided between said wall and flange if the flange is pressed against said wall in 20 the filling operation.

5. A filling valve comprising a plug, and a flexible resilient hollow open ended body having a neck portion at one end and terminating at the other end in an edge normally in sealing contact 30 with said plug, said body being circumferentially bulged between said neck and edge and the bulged portion having an internal annular recess so that the body portion adjacent said edge is in the form of a freely flexing flange, said flange flexing 35 when engaged by the lip of a container during a filling operation to free said edge from the plug to permit flow between said edge and plug, the container lip forming a seal.

6. Filling apparatus comprising a tank, a boss 40 projecting below the tank and having a vertical axial through opening registering with an opening in the tank bottom, said boss having a reduced lower end portion surmounted by an annular downwardly faced external shoulder, a vent tube 45 passed through said openings in spaced relation to the walls thereof, said vent tube having at its lower end a circumferential enlargement providing a top substantially conical surface, means supporting said vent tube with said enlargement 50 below said boss, and a hollow open-ended flexible resilient body comprising a neck portion surrounding and frictionally gripping the reduced lower end of said boss with the top of said neck portion abutting said shoulder, the walls of said body being circumferentially contracted below 55 said neck portion to an edge normally having sealing contact with said conical surface in spaced relation to the vent tube, the body portion adjacent said edge being in the form of a freely 60 flexing flange extending toward the vent tube, said flange flexing when engaged by the lip of a container during a filling operation to free said edge from said surface to prevent flow between said edge and surface, the container lip forming a seal with said flange. 65

7. Apparatus according to claim 6 wherein the supporting means for the vent tube is constituted by an internal upwardly faced shoulder in the 70 boss, a vertically ribbed member resting on said upwardly faced shoulder and centering the vent tube relative to the boss opening, and an abutment on the vent tube resting on top of said member. 75

8. Filling apparatus comprising a tank, a boss projecting below the tank and having a vertical axial through opening registering with an opening in the tank bottom, said boss having a reduced lower end portion surmounted by an annular downwardly faced external shoulder, a vent tube passed through said openings in spaced relation to the walls thereof, said vent tube having at its lower end a circumferential enlargement 10 providing a top substantially conical surface, means supporting said vent tube with said enlargement below said boss, and a hollow open-ended flexible resilient body comprising a neck portion surrounding and frictionally gripping the reduced lower end of said boss with the top 15 of said neck portion abutting said shoulder, the walls of said body being circumferentially externally convexed and internally concaved below said neck portion and terminating in an edge normally in sealing contact with said conical surface in spaced relation to the vent tube, the body walls adjacent said edge being downwardly tapered at a slight angle to the horizontal and being free flexing away from said conical surface, the body portion adjacent said edge being 20 in the form of a freely flexing flange extending toward the vent tube, said flange flexing when engaged by the lip of a container during a filling operation to free said edge from said surface to prevent flow between said edge and surface, the container lip forming a seal with said flange.
9. For use as a valve and sealing element in filling apparatus, a flexible resilient hollow open-ended body having a relatively thick walled neck portion and a relatively thin walled bulbiform portion, the latter terminating in a thin marginal portion defining an edge adapted to cooperate as a valve element with a plug, the body portion outwardly of said edge having a substantially flat 25 external surface adapted to cooperate with a container lip to form a seal with the top of the latter during a filling operation and said body

portion being axially collapsible as a result of its sealing contact with the container lip whereby said edge is movable away from said plug.

10. Filling apparatus comprising a tank and a down spout in communication with the tank, 5 said spout having interiorly an upwardly faced shoulder, a tubular member having vertical external ribs supported on said shoulder, a vent tube passing through said down spout and tubular member, an abutment secured to the vent tube and resting on top of said tubular member, and valve means for controlling flow through said down spout.

11. A sealing member comprising a hollow open-ended body of freely flexing resilient material, 10 said body having an internal annular enlargement which has opposed internal end surfaces, at least one of said surfaces being configured to provide a vent so as to obviate the vacuum effect which might otherwise occur upon axial collapse of said body to such an extent in use as to bring said surfaces together.

12. A filling valve comprising a plug, and a flexible resilient hollow open-ended body having a neck portion at one end and terminating at 2 the other end in an edge normally in sealing contact with said plug, said body having an internal annular recess inwardly of said edge so that the body portion adjacent said edge is in the form of a freely flexing flange, said flange flexing when engaged by the lip of a container during a filling operation to free said edge from the plug to permit flow between said edge and plug, the container lip forming a seal with said flange, said recess having opposed internal end surfaces of which at least one is configured to provide a vent so as to obviate the vacuum effect which might otherwise occur upon axial collapse of said body to such an extent in use as to bring said surfaces together.

ROBERT J. STEWART.
